COMBINED MASSAGE ROLLER AND REDUCING EXERCISER

Camille I. Ziglin, 239 Emerling Drive, St. Louis, Mo.

Filed May 24, 1965, Ser. No. 85,421

Term of patent 14 years

(Cl. D83—1)

FIG. 1

FIG. 2

FIG. 1 is a plan view of the invention, showing my new design, the reverse view being identical;

FIG. 2 is a side elevational view thereof, the opposite side being identical.

I claim:

The ornamental design for a combined massage roller and reducing exerciser, as shown and described.
